UNITED STATES PATENT OFFICE.

CONSTANCE MABEL MEREDITH HOUSTON, OF PAPANUI, NEW ZEALAND.

RECEPTACLE FOR CONTAINING LIQUIDS.

1,261,028.

Specification of Letters Patent.

Patented Apr. 2, 1918.

Application filed May 15, 1917. Serial No. 168,762.

To all whom it may concern:

Be it known that I, CONSTANCE MABEL MEREDITH HOUSTON, a subject of the King of Great Britain, residing at 83 Knowles street, Papanui, in the Dominion of New Zealand, have invented new and useful Improvements in and Relating to Receptacles for Containing Liquids, of which the following is a specification.

10 This invention relates to tins, cans, barrels and the like receptacles adapted to contain liquids, its object being to provide convenient means whereby any solid matter may be retained in such receptacle when pouring out the contents.

In carrying this object into effect, the invention consists of a bag or strainer of bulbous form, composed of fine wire gauze and arranged within the receptacle so as to 20 cover the orifice through which the contents are poured. The said strainer may be permanently mounted in the receptacle in the course of manufacture of the latter or such strainer may be detachably arranged 25 and adapted to be received by a suitable formation provided for the purpose in the receptacle.

In order that the nature of the invention and its construction may be fully understood, reference will now be made to the accompanying sheet of drawings in which:—

Figure 1— is a perspective view of a tin indicating in dotted lines the position of the strainer permanently attached therein,

35 Fig. 2 is an enlarged detail view showing in section one form of apparatus for detachably securing a strainer within the discharge opening of a receptacle.

40 1 is the receptacle which may take any desired form such for instance, as the ordinary rectangular tin commonly used for containing petroleum and other liquids as shown in Fig. 1, or such may consist of a drum or cask of wood, metal or other material.

45 According to the present invention, a bag or strainer 2 is provided and arranged within the receptacle 1 so as to cover the orifice through which the contents are to be poured.

50 As shown in Fig. 1, the strainer 2 may be soldered or otherwise permanently attached

to the inner surface of the receptacle in the course of manufacture, the position of such strainer being suitably indicated upon the outer surface of the receptacle to insure of the hole being pierced at the required spot. 55

Referring now to Fig. 2, I have here shown one wall of the receptacle 1, such wall being formed with a circular discharge opening 10, to receive the strainer 2. The wall of this opening is provided with an 60 inturned annular threaded flange 3, in which is mounted an annular metallic collar 4. The lower edge of the collar 4 is secured to the strainer 2, as shown, whereby the strainer is supported in depending position 65 in the receptacle, as will be understood. The collar 4 is screw-threaded throughout its entire width, as indicated at 5, certain of such threads coöperating with the thread of the flange 3 to support the collar within 70 the opening, as will be understood. The collar 4 is of such a width that its upper edge projects exteriorly of the receptacle, as at 7, and this projected portion receives a screw cap 6 which closes the opening and seals the 75 contents of the receptacle.

To prevent accidental movement of the collar 4 and subsequent displacement of the strainer 2, and to form a positive seal for the discharge opening of the receptacle, I 80 provide a bung 8, which, as here shown, is mounted within the collar 4 and threadedly engages the same. When applying the bung 8, it will be understood that it is inserted prior to the application of the cap 6, and that when in position it will cause a radial 85 distention of the collar 4, thus causing the same to be locked into engagement with the flange 3 and thereby preventing circumferential movement of the collar and producing an effective seal between the collar and the flange. It will be readily understood that the strainer may be easily removed for cleaning purposes by unscrewing the cap and bung in the order named, whereby the collar 90 may then be gripped and rotated to withdraw the same from the opening. 95

I claim:—

In combination, a receptacle having an opening formed therein, the wall of said 100

opening being inturned and threaded, a collar screw threaded throughout its length and threadedly engaging the wall of said opening and having the major portion thereof disposed exteriorly of said receptacle, a foraminous member secured to said collar and disposed within the receptacle, a bung within said collar and threadedly engaging

the same, and a screw threaded closure cap threadedly engaging said collar.

10

In testimony whereof I affix my signature in presence of two witnesses.

CONSTANCE MABEL MEREDITH HOUSTON.

Witnesses:

PERCY RICHMOND CLIMIE,
JOHN HENRY STRINGER.
